JAN MORRIS, OF DANVERS, MASSACHUSETTS.

PERMUTATION-LOCK.

1,357,581.

Specification of Letters Patent.

Patented Nov. 2, 1920.

Application filed June 8, 1920. Serial No. 387,370.

To all whom it may concern:

Be it known that I, JAN MORRIS, citizen of Poland and resident of Danvers, in the county of Essex and State of Massachusetts, 5 have invented certain new and useful Improvements in Permutation-Locks, of which the following is a specification.

This invention relates to permutation safety locks, and has for its main object the 10 provision of a lock which may be opened only by a step-by-step operation with which the operator must be entirely acquainted.

The above and other objects will become apparent in the description below, in which 15 characters of reference refer to like-named parts in the drawings.

Referring briefly to the drawings, Figure 1 is a plan view of my lock with the cover removed.

20 Fig. 2 is a similar view with the respective operating parts in another relative position.

Fig. 3 is a sectional view taken on the line 3—3 of Fig. 2.

25 Fig. 4 is a sectional view taken on the line 4—4 of Fig. 1.

Fig. 5 is a perspective view of a safe showing the bolts of my lock extending from the door thereof.

30 Fig. 6 is a sectional view taken on the line 6—6 of Fig. 2.

Fig. 7 is a perspective view of the door of the aforementioned safe.

Fig. 8 is a sectional view taken on the line 35 8—8 of Fig. 1.

Referring now in detail to the drawings, the numeral 1 represents the back frame support of my lock and 2 a panel attached thereto upon which a member 3 is slidably 40 mounted. A frame 4 having a substantially U-shaped side wall 10, is slidably attached to the rear of said slideable member, and a curved band 5 of rigid material such as metal is attached to the frame 4. An eccentric or cam 6 is pivotally mounted in the panel 2 at 7, said cam adapted to contact with said band 5. Springs 8 are mounted within the frame 4, in contact at one end with said frame and at the other with the 50 member 3. Additional springs 3^a (Fig. 6) are attached at one end to the panel 2 and at the other to the member 3, by means of the eyes shown. Slots 9, 50, and 51 extend along the body of the member 3; the sides 55 of the frame 4 are adapted to slide in the slots 50 and 51, and the pin 9^a, rigid with

said frame, slides in the slot 9; thus the frame 4 is resiliently slideable toward or away from the member 3. Guides 11 and 12 are rigid with the back 1 and guide the member 3 in its slideable motion. On each side of the member 3 the same is provided with right angled shoulders 13, 14. Through openings in either side of the frame 1 bolts 15 and 16 are adapted to slide. Said bolts 65 are provided with pins 17 and 18, respectively, projecting upward therefrom.

The member 3 is provided with a nose or finger 19 extending therefrom, as shown. Adjacent said nose, and forward therefrom, 70 lies a drum 20 pivotally mounted in the frame 1. A plurality of wire rings (four are shown) surround said drum, and each of said rings is provided with a pin-like radial extension, said extensions being of 75 different sizes; for instance, the ring 21 has an extension of, say, $\frac{1}{8}$ th inch, that 22, $\frac{1}{4}$ th inch; that 23, $\frac{1}{2}$ inch; that 24, $\frac{5}{8}$ ths inch. Said rings are loose on the drum, and are circumferentially slideable; they are also not 80 continuous, the ends of each being mutually separated by a distance slightly greater than the width of the nose 19. A slot 25 extends longitudinally throughout the length of the drum 20 and radially through 85 the periphery of the drum.

A beam 26 having its inner edge arcuately formed at 26°, and being slidably supported in brackets 27—28, rests against the panel 2. Slots 29 and 31, respectively, are 90 provided in said brackets and pins 30 and 32, respectively, engage said slots. Links 33 and 34, respectively, are pivoted to the ends of the member 26, and are in turn connected to bell cranks 35, 36. The free ends 95 of said cranks contact with the pins 17 and 18. The inner ends of the bolts 15 and 16 are thickened to provide shoulders 39 and 40, against which the ends of springs 41 and 42, respectively, lie. These springs are supported in the frame by pins 43 and 44, respectively, and the other ends of the same press against the walls of the casing or frame 1.

A cover 45 is attached to the frame 1 to 105 inclose the same. A handle 46 is attached to the drum 20 through the medium of a shaft 48, and a handle 47 is attached to the shaft or pivot 7. Both of these handles are on the outside of the frame 1, and they are 110 peripherally graduated as shown in Fig. 7.

The operation of the lock is as follows:

Assume the parts to lie in the positions shown in Fig. 2, that is, that the lock is closed. To open the lock, which means, to draw the bolts 15 and 16 in, is impossible to one not acquainted with the proper sequence of steps. Should one turn the handle 47, the cam 6 would advance the member 3, but the advance of said member is limited by its nose 19, which would strike the rings on the drum 20. As aforementioned, each ring has an opening in its periphery large enough to permit said nose to pass through; but in each ring said opening is located at a peripheral distance from the extension of that ring which is different from the similarly-defined distances on all the other rings. The nose, then, would strike the rings, and thus the member 3 could not advance far enough to allow the bolts 15 and 16 to move inward, since said bolts would still engage the sides of said member. However, by first manipulating the handle 47 to advance the member 3 a short distance so that the nose 19 will lie in the orbit of the end of the extension 25 of the ring 21, and then turning the handle 46 until the opening in the ring 21 will coincide with the slot 25, the first step in the opening of the lock will have been accomplished. Then the handle 47 will be rotated again until the nose 19 is clear of the extension of the ring 21, but will lie in the orbit of the end of the extension of the ring 22; then again the handle 46 is turned until the opening in the ring 22 coincides with the slot 25. Then the member 3 is again withdrawn a slight distance, and the opening in the ring 23 brought into coincidence with the slot 25. And similarly the opening in the ring 24 is brought into coincidence with said slot. Then, the handle 46 is again turned until the slot lies directly in the path of the nose 19. Finally, then, the handle 47 is turned until the member 3 has advanced so that the nose 19 will have passed through the aligned openings in the rings and into the slot; then the sides of the shoulders 13 and 14 will have cleared the inner ends of the bolts 15 and 16, and the latter will be drawn in by the force of 40 the springs 41 and 42. To close the lock, the cam 6 (handle 47) is turned so that said cam forces the beam 26 to the left, thus forcing the bolts outward. When they have been forced all the way outward, the force 45 of the springs 3^a will pull the member 3 back and thus the shoulders 13 and 14 will keep the bolts locked in their extended position, as originally.

In Fig. 5 I have illustrated one manner of utilizing my lock, in combination with a 60 safe door, the safe being shown at 55 and the door thereof at 56.

It is thus apparent that I have provided a permutation lock which will be inoperable to one not acquainted with the specific operation thereof. Of course, the graduations on the handles 46 and 47, and on the face of the case 1, are provided as a guide to the positions of the operating parts of the lock, so that, with proper calibration, the position 70 of each of the operative parts in the lock will be determined by the positions of the handles 46 and 47, as is common with combination locks.

I claim:

1. A permutation lock comprising a casing, a member slidable therein, guides for said member, a cam pivotally mounted adjacent the rear end of said member and adapted to move said member, resilient means between said cam and said member, a nose on the forward end of said member, a drum pivotally mounted in said casing adjacent the forward end of said member, a radial slot in said drum, a plurality of rings loosely mounted on said drum and having openings in their peripheries of a length equal to the peripheral width of said slot, radial extensions of different lengths on said rings, a slideable bolt on each side of said member, resilient means normally urging said bolts toward said member, a slideable beam adjacent said cam, links connecting the ends of said beam with said bolts, and means for manipulating said drum and said cam.

2. A permutation lock comprising a casing, a member slidable therein, means for guiding said member, a cam pivotally mounted adjacent the rear end of said member, resilient means between said cam and said member, a beam slidably mounted adjacent said cam, bolts slidably mounted on the sides of said member, means urging said bolts normally toward said member, an extension on the forward end of said member, a drum pivotally mounted adjacent said forward end, said drum normally limiting the advance of said member, and means on said drum for allowing said member to advance beyond the distance limited as aforementioned.

Signed at Salem in the county of Essex and State of Massachusetts this 3rd day of June, A. D. 1920.

JAN MORRIS.
